(57) CLAIM

The ornamental design for a bottle, as shown and described herein.

DESCRIPTION

FIG. 1 is a top perspective view of a first embodiment of a bottle, showing my new design.

FIG. 2 is a partially enlarged top perspective view thereof, taken from FIG. 1.

FIG. 3 is a front view thereof.

FIG. 4 is a rear view thereof.

FIG. 5 is a first side view thereof.

FIG. 6 is a second side view thereof.

FIG. 7 is a top view thereof.

FIG. 8 is a bottom view thereof.

FIG. 9 is an exploded perspective view thereof.

FIG. 10 is an exploded view thereof.

FIG. 11 is a cross-section view thereof, taken along line 11-11 in FIG. 1.

FIG. 12 is a top perspective view of a second embodiment of a bottle, showing my new design.

FIG. 13 is a partially enlarged top perspective view thereof, taken from FIG. 12.

FIG. 14 is a front view thereof.

FIG. 15 is a rear view thereof.

FIG. 16 is a first side view thereof.

FIG. 17 is a second side view thereof.

FIG. 18 is a top view thereof.

FIG. 19 is a bottom view thereof.

FIG. 20 is an exploded perspective view thereof.

FIG. 21 is an exploded view thereof.

FIG. 22 is a cross-section view thereof, taken along line 22-22 in FIG. 12.

FIG. 23 is a top perspective view of a third embodiment of a bottle, showing my new design.

FIG. 24 is a partially enlarged top perspective view thereof, taken from FIG. 23.

FIG. 25 is a front view thereof.

FIG. 26 is a rear view thereof.

FIG. 27 is a first side view thereof.

FIG. 28 is a second side view thereof.

FIG. 29 is a top view thereof.

FIG. 30 is a bottom view thereof.

FIG. 31 is an exploded perspective view thereof.

FIG. 32 is an exploded view thereof; and,

FIG. 33 is a cross-section view thereof, taken along line 33-33 in FIG. 23.

The bottle has been shown with symbolic breaks. The appearance of any portion of the article between the break lines forms no part of the claimed design.

The dot-dash broken lines immediately adjacent to the claimed areas in the views represent the boundaries of the design and form no part thereof.

The dot-dot-dash broken lines of FIGS. **1, 2, 12, 13, 23, 24** are included to show partially enlarged views only and form no part of the claimed design.

The evenly-spaced broken lines in the figures illustrate the portions of the bottle and form no part of the claimed design. None of the broken lines form any part of the claimed design.
